PIPE AND COIL CLEANER APPARATUS

Josef Schecki, Brooklyn, N. Y., assignor to
Herbert Horwitz, New York, N. Y.

Application March 15, 1957, Serial No. 646,437

2 Claims. (Cl. 15—3.51)

This invention relates to devices for cleaning pipes and coils of pipes and apparatus, and is directed particularly to devices adapted for the use of hard, swirling beads for that purpose.

Pipes normally used to convey beer, milk and other liquids often become fouled with deposits or incrustations from such liquids, which materially affect them.

In some cases, the deposits may be removed by mechanical means. In more instances, owing to the coiled configuration of the piping as in the dispensing of beer, it is not possible to do so. In that case it is necessary to use a detergent solution and cause it to circulate repeatedly through the pipe. Next the pipe must be carefully rinsed with water to remove the cleaning solution. This method is both time-consuming and expensive because of the uneconomic utilization of detergent.

It has been proposed to employ cleaning beads for cleaning pipes, but even though this proposal was made over twenty-five years ago, it has not been followed, because the device employing the same were not able to operate at full pressure, lost the beads in various ways, or failed to use them efficiently.

The principal object of my invention is to provide a cleaning apparatus of the above nature which is readily adaptable for use in cleaning pipes in a wide variety of liquid flow pipe systems.

Another object of my invention is to provide a pipe cleaning apparatus of the character described which is efficient in operation, and which allows ready continuous inspection during operation of the degree to which cleaning has been accomplished.

It is another object of my invention to provide a pipe cleaning apparatus of the above nature which forces a quantity of hard, swirling beads through the pipes being cleaned, and which is actuated by the pressure of the water to automatically periodically change the direction in which the water and beads are being forced through the pipes.

It is still another object of my invention to provide a pipe cleaning apparatus of the above nature to which a motor can readily be attached for increasing water pressure where service pressure is too low for efficient operation, or where more vigorous cleaning action is desired in a particular case.

Other objects, features and advantages of my invention will be apparent from the following description, especially when read with reference to the accompanying drawings.

In the drawings, wherein like reference numerals denote corresponding parts throughout the several views:

Fig. 1 is a longitudinal cross-sectional view of a pipe cleaner embodying the invention;

Fig. 2 is another partially schematic view of the flow reversal slide valve portion of a manually operated modification shown with the valve in its uppermost position; and

Fig. 3 is a horizontal cross-sectional view of the slide valve taken along the line 3—3 of Fig. 2 in the direction shown by the arrows.

Referring now in detail to Fig. 1, the improved pipe cleaner, designated generally by reference numeral 10, comprises a water turbine actuating mechanism 12, a flow reversal valve 14 and a two-part flow chamber 16.

The water turbine flow mechanism 12 comprises a water input conduit 18 which is enlarged at one side to form a cylindrical turbine wheel housing 20 from which a conduit 22 leads to the slide valve 14. A turbine wheel 24 is rotatably journaled within the housing 20 and operative to be turned by the pressure of water flowing through water input conduit 18. The turbine wheel shaft at the outside of the housing 20 is fitted with a pinion gear 26 in mesh with an intermediate gear 28. The intermediate gear 28 is fixed to a rotatably journaled shaft 30 upon which is fixed a pinion gear 32. The pinion gear 32 is in mesh with a rotatably journaled valve actuating gear 34 provided with an outwardly-extending off-center pin 36, which controls operation of the slide valve 14 in the manner hereinbelow more fully described.

The flow reversal slide valve 14, preferably constructed of brass, comprises a cylindrical housing 38 having a central cylindrical bore 40. The housing 38 is provided in its side wall with an upper pair of aligned opposed openings 42, 44, and a lower pair of aligned opposed openings 46, 48. The water supply conduit 22 connects with the upper opening 44 and a discharge conduit 50 connects with the lower opening 48. Slidably disposed within the housing 38 is a cylindrical slide member 52 having an upper annular concavity 54 and a lower annular concavity 56. With the position of the slide member 52 in the housing 38 as illustrated in Fig. 1, the upper and lower annular concavities 54 and 56 are in register with the upper and lower pair of aligned opposed openings 42, 44 and 46, 48, respectively, so that there is communication between the openings 42 and 44, and between the openings 46 and 48. The slide member 52 is also provided with a pair of crossing, longitudinally-extending S-bores 58, 60 operative, when said slide member is in its uppermost position as illustrated in Fig. 2, to effect communication between openings 44 and 46, and between openings 42 and 48 in the housing 38.

The upper end of the slide member 52 is provided with a cylindrical bore 62 within which is resiliently constrained by means of upper and lower coil springs 64, 66 a circular flange fixed at the lower end of a connecting rod 70. The upper coil spring 64 is held in place by a screw cap 72 threaded in the upper end of the bore 62. A bushing cap 74 screwed about the upper end of the housing 38 seals the slide member 52 with respect thereto.

The upper end of the connecting rod 70 is secured to a rectangular follower cage 76 within which projects the off-center pin 36 of the valve-actuating gear 34. Off-center turning of the pin 36 in the cage 76 operates to move the connecting rod 70 from one vertical position to another during each half circle of revolution of the gear 34, whereby the slide member 52 will be moved in the valve housing 38 from the position illustrated in Fig. 1 solid lines to the position illustrated by dotted lines, and back again to the position illustrated in solid lines for each full circle of revolution of the gear. Detent means are provided for temporarily resiliently locking the slide member 52 in one or the other of its two operating positions, and comprise a detent plunger 78 resiliently supported within an opening in a boss 80 formed at the lowermost end of slide valve housing 38 by means of a spring 82 and screw cap 84. The inner end of the detent plunger 78 enters one or the other of grooves 86 and 88 provided in the lower end of the slide member 52, depending upon in which of the two operating positions the slide member is. The resiliency of the springs 64 and 66 operating upon the connecting rod 70, serves to

65

70

provide rapid snap action in the movement of the slide member from one position to the other so that blocking of water flow during operation of the device due to valve switching is kept to a minimum.

The two-part flow chamber 16 comprises a base cap member 90 at its lower end, a top cap member 92 at its upper end and a central divider wall member 94 held in spaced relation by an upper cylindrical glass wall 96 and a lower cylindrical glass wall 98, the whole assembly secured together by a central bolt 100 to provide upper and lower sealed chambers 102 and 104. The upper ends of the chambers 102 and 104 are fitted with wire mesh screens 106 and 108, respectively. Contained within the two-part flow chamber 16 are a quantity of spherical glass beads 110 which are washed between the upper and lower chambers 102 and 104 through the pipes being cleaned when the device is in operation, as is hereinbelow more fully explained. These beads should be preferably about 0.005 inch in diameter and are obtainable from Acme Glass Products, 17 East 17th Street, New York 3, N. Y.

A conduit 112 is connected between an opening 114 in the top cap member 92 and the upper opening 42 in the valve slide housing 38. An opening 116 in the divider wall member 94 and communicating with the lower chamber 104 is connected by means of a conduit 118 to the lower opening 46 in the valve slide housing 38. An opening 120 in the divider wall member 94 and communicating with the lower end of the upper chamber 102 is connected with an output conduit 122, and an opening 124 in the base cap member 90 and communicating with the lower end of the lower chamber 104 is connected with an output conduit 126.

The outer ends of output conduits 122 and 126 expand into flanges 128, 130, which join with respective expanded ends of output conduits 132, 134 to form chambers 136, 138 within each of which is disposed in fixed position a bundle of short twisted metal tubes 140, 142 of a diameter sufficient to permit passage of beads 110 therethrough, which serve to impart a twisting force to the water and the glass beads 110 as they flow into the pipes being cleaned.

In operation, the force of water flowing through the input conduit 18 will revolve the turbine wheel 24 setting the valve slide mechanism in operation through the speed reduction mechanism composed of the gears 26, 28, 32 and 34. When the slide valve 14 is in the position of operation illustrated in Fig. 1, water will flow through conduits 22 and 112 as indicated by the arrows, and into the upper chamber 102 through the wire mesh screen 106. The water under pressure will then be forced, together with the crystal pearls 110, through output conduit 122 and through the twisted metal tubes 140 into the pipe to be cleaned with a twisting motion to achieve maximum cleaning action and remove adherent matter. The water and crystal beads will return through conduit 126 into the lower chamber 104, where they will be separated by the screening action of the wire mesh 108. The water will be discharged from the lower chamber 104 through conduit 118, through the opening formed by the annular groove 56, and through discharge conduit 50.

When the slide valve is in the position illustrated in Fig. 2, the water will flow in the reverse direction through the lower and upper chambers 104, 102, as indicated by the flow arrows in Fig. 2, so that the water and beads will flow from the lower chamber back through the bundle of twisted tubes 142 and through the pipe being cleaned into the upper chamber, where the crystal pearls will remain by virtue of the screening action of wire mesh screen 106 and from which the used water will be discharged through conduit 112, 8-bore 60, and discharge conduit 50. The clarity of the water flowing through the tube being cleaned can be observed in the chambers 102, 104 through their glass or transparent

plastic walls, to provide constant supervision of the cleaning operation progress.

If the supply water pressure is too low for proper cleaning and actuation of the valve mechanism, an electric motor can be applied to the turbine gear mechanism for force feeding.

A still less complicated modification which has given excellent results is illustrated in Fig. 2. In this embodiment, connecting rod 70 by means of which water reversal is achieved, is operated manually by means of a handle 150 pivoted at 152 on a support 154 mounted on top cap 92. To facilitate manual operation, spring means 64 and 66 shown in Fig. 1 are omitted. The loose connection between handle 150 and valve stem may be conventional, such being schematically shown in Fig. 2.

In operation when the observer sees that all the beads have settled in, for example, chamber 102, he moves handle 150 the opposite way to reverse water flow and cause the beads to re-circulate or reciprocate through the pipe to be cleaned.

In the case of particularly strongly adherent matter, it may be desirable to use certain chemicals of an acidic or basic character suitable for dissolving such matter, in conjunction with the beads. Such chemicals may be introduced with the cleaning water or together with the beads.

Obviously the apparatus of the invention may be adapted for the simultaneous cleaning of many pipes in which case a plurality of chambers such as 102 and 104 as well as several additional conduits leading to the pipes are necessary.

While I have described a preferred embodiment of my invention, it is to be understood that various changes in shape or proportion, as well as the substitution of equivalent elements for those herein shown and described may be made without departing from the spirit of my invention and the principles involved.

What is claimed is:

1. In apparatus for cleaning a liquid flow pipe, the combination comprising a first chamber having an output conduit in communication with the interior thereof, a second chamber having an output conduit in communication with the interior thereof, said conduits being adapted for connection to the ends of a pipe to be cleaned, means for supplying cleaning water, reciprocable valve means interconnecting said first and second chamber members with said water supply means and operative when actuated to alternately conduct water into one of said chamber members and then to the other, said valve means comprising means for discharging water from the chamber to which water is not being conducted, a quantity of hard beads in said chambers, screen means for preventing said beads from entering said valve means; automatic means controlled by said water supply means for periodically shifting said valve means to force said water and beads back and forth through the pipe to be cleaned, said automatic means comprising a water turbine in the water supply means upstream of said valve means, a cage member resiliently connected to said reciprocable valve means, and an eccentrically rotating pin actuated by said water turbine and disposed within said cage member.
2. The combination of claim 1, wherein at least one of said chambers is transparent to permit visual inspection of the flowing liquid.
